UNITED STATES PATENT OFFICE

ERIK CLEMMENSEN, OF NEWARK, NEW YORK, ASSIGNOR TO MATHIESON ALKALI WORKS, INC., OF NEW YORK, N. Y., A CORPORATION OF VIRGINIA

PROCESS OF MAKING ORGANIC INTERMEDIATES

No Drawing.

Application filed August 13, 1926. Serial No. 129,089.

This invention relates to the production of organic intermediates and particularly to processes of substituting the halogen in halogen-nitrobenzenes with an alkoxy group 5 to form alkoxy-nitrobenzenes, and has as a general object the production of such compounds in a convenient, efficient and economical manner.

A more specific object of the invention is 10 to provide a process of preparing alkoxy-nitrobenzene from halogen-nitrobenzenes in approximately quantitative yields, at normal pressure and at relatively low temperatures.

15 Other objects of the invention will in part be obvious and will in part appear herein-after.

The invention accordingly comprises the several steps and the relation and order of 20 one or more of such steps with respect to each of the others thereof, which will be exemplified in the process hereinafter disclosed, and the scope of the application of which will be indicated in the claims.

25 Experimental attempts have been made to prepare these compounds by heating the halogen-nitrobenzenes with metallic alcoholates but, due to the steps employed, various side reactions occurred resulting in the formation of azo and azoxy compounds and the 30 yields of alkoxy-nitrobenzenes was consequently small.

Commercial methods of preparing the alkoxy-nitrobenzenes have therefore either 35 utilized materials of an entirely different type or have resorted to the use of caustic alkalis and water to decrease the violence and rapidity of the reaction, in an endeavor to minimize the loss due to the side reactions. Heating under pressure was frequently used in such processes, the materials 40 were generally all present at the beginning and the yields were unsatisfactory for economical commercial operation.

45 I have discovered that the aforesaid side reactions may be substantially entirely avoided, and approximately theoretical yields of alkoxy-nitrobenzenes may be obtained from the halogen-nitrobenzene used, if the metallic alcoholate, prepared by dissolving an alkali

metal in dry alcohol, is slowly added to the heated halogen-nitrobenzene. By such procedure I have found that although the temperature and pressure may be varied within quite wide limits, nevertheless it is both convenient 55 and practical to carry out the reaction at relatively low temperatures, as, for example, at about the boiling point of the alcohol used.

As a result of the possibility of using such temperatures, it is not necessary that the halogen-nitrobenzene be diluted with alcohol, as heretofore, although, due to the tendency to thicken during the reaction, such dilution is generally desirable. Also I have found that other substances may be used as a diluent, although the use of alcohol is preferred since it can then subsequently be distilled off from the mass and used directly again without purification.

The following example is illustrative of 70 the manner in which my process may be practised:

In the preparation of ortho-nitroanisole, 157.5 parts by weight of ortho-nitrochlorobenzene is mixed with an equal weight of 75 methyl alcohol and heated to about 70° C. under a reflux. A solution of 23 parts by weight of metallic sodium dissolved in about 200 parts of methyl alcohol is added slowly at a rate such that there is at no time present a substantial excess of the alcoholate. The 80 temperature is maintained at about 70° C., the time of addition being about 48 hours. Thereafter the methyl alcohol is distilled off and enough water is added to the remainder 85 to dissolve the formed sodium chloride. At this time the ortho-nitroanisole separates as a layer on top of the sodium chloride solution and may be separated in the usual way. The 90 yield is substantially quantitative.

Although the above example is illustrative only of the process of preparing ortho-nitroanisole, yet it is to be understood that my invention is applicable to the preparation of other compounds of a similar nature, such as, 95 para-nitroanisole, di-nitroanisole etc., and that other halogen-nitrobenzenes such as para-nitrochlorobenzenes, di-nitrochlorobenzene etc., and other alcoholates such as ethyl alcoholate etc., and other alkali metals may 100

be used if desired; also as pointed out above, other temperatures may be used; a particular feature being that the metallic alcoholate is added to correspond to the halogen-nitrobenzene slowly so that the reaction is substantially complete for the materials present at any given instant.

Since certain changes may be made in carrying out the above process without departing 10 from the scope of the invention, it is intended that all matter contained in the above description shall be interpreted as illustrative and not in a limiting sense.

It is also to be understood that the following 15 claims are intended to cover all of the generic and specific features of the invention herein described, and all statements of the scope of the invention which, as a matter of language, might be said to fall therebetween.

20 Having described my invention, what I claim as new and desire to secure by Letters Patent is:

1. A process of making an alkoxy-nitrobenzene which includes slowly adding a metallic 25 alcoholate to a halogen-nitrobenzene while maintaining the mixture at substantially atmospheric pressure and at an elevated temperature.

2. A process of making an alkoxy-nitrobenzene which includes slowly adding a metallic 30 alcoholate to a halogen-nitrobenzene in the presence of a solvent of the latter compound while maintaining the mixture at substantially atmospheric pressure and at an 35 elevated temperature.

3. A process of making an alkoxy-nitrobenzene which comprises slowly adding an alcoholic 40 solution of a metallic alcoholate to a halogen-nitrobenzene while holding the mixture at a temperature of approximately the boiling point of the alcohol and at substantially atmospheric pressure.

4. A process of making an alkoxy-nitrobenzene which comprises slowly adding an alcoholic 45 solution of a metallic alcoholate to a halogen-nitrobenzene at a rate such that there is at no time present a substantial uncombined quantity of unreacted alcoholate, while holding the mixture at a temperature 50 of approximately the boiling point of the alcohol and at substantially atmospheric pressure.

5. A process of making a nitroanisole which 55 includes slowly adding a solution formed by dissolving an alkali metal in methyl alcohol to a halogen-nitrobenzene while maintaining the mixture at substantially atmospheric pressure and at an elevated temperature.

6. A process of making a nitroanisole which 60 includes slowly adding a solution formed by dissolving an alkali metal in methyl alcohol, to a halogen-nitrobenzene, while holding the mixture at about 70° C.

7. A process of making a nitroanisole which 65 comprises slowly adding a solution

formed by dissolving an alkali metal in methyl alcohol to a halogen-nitrobenzene at a rate such that there is at no time present a substantial quantity of unreacted alcoholate, while holding the mixture at about 70° C.

8. A process of making ortho-nitroanisole which comprises dissolving ortho-nitrochlorobenzene in methyl alcohol, heating to about 70° C. under a reflux, and, while maintaining the temperature substantially constant, slowly adding a solution formed by dissolving an alkali metal in methyl alcohol.

9. A process of making ortho-nitroanisole which comprises diluting 157.5 parts by weight of ortho-nitrochlorobenzene with approximately an equal amount of methyl alcohol, heating the mixture to about 70° C. under a reflux, and, while maintaining the temperature substantially constant, adding to the mixture a solution formed by dissolving 23 parts by weight of metallic sodium in about 200 parts of methyl alcohol, the addition being made at a rate such that there is at no time present a substantial quantity of unreacted alcoholate.

In testimony whereof I affix my signature.

ERIK CLEMMENSEN.
